THREAD-PARTING MECHANISM FOR LOOMS.

979,779.

Specification of Letters Patent. Patented Dec. 27, 1910.

Application filed August 19, 1910. Serial No. 577,938.

To all whom it may concern:

Be it known that I, JAMES MARCURE, a citizen of the United States, and resident of Pawtucket, county of Providence, State 5 of Rhode Island, have invented an Improvement in Thread-Parting Mechanism for Looms, of which the following description, in connection with the accompanying drawing, is a specification, like characters on the 10 drawing representing like parts.

This invention relates to thread parting mechanism employed on automatic filling-replenishing looms to sever the old or spent filling adjacent the shuttle, upon a change 15 of filling, the filling thread being parted and clamped by a suitable device and while clamped the severed piece is brought into position to be cut adjacent the cloth by a temple thread-cutter. Looms so equipped 20 are well known in the art, and United States Patent No. 701,938 granted June 10, 1902 to Roper is one example of such a structure, and means is therein shown for catching between jaws the severed piece of thread and 25 gradually working it forward and out of the way. This is to prevent such piece of thread from being caught by the fresh filling and carried by it into the cloth.

In my present invention the combined 30 thread parter and clamp is bodily movable into position to act upon the old or spent filling adjacent the cloth, and between the parting and clamping device and the edge of the cloth I provide a novel thread-re- 35 mover comprising a fixed support for the severed piece of thread and a co-operating, intermittingly rotated brush to sweep the severed pieces forward on the support and out of the way of the fresh filling.

The novel features of my invention will be fully described in the subjoined specification and particularly pointed out in the following claims.

Figure 1 is a transverse section of a portion of an automatic filling-replenishing loom provided with thread parting and clamping mechanism, and with a thread-re- 50 mover embodying one form of my present invention; Fig. 2 is an enlarged detail in side elevation of the thread-remover; Fig. 3 is a top plan view thereof, also enlarged.

Referring to Fig. 1 the lay A¹, filling- 55 feeder F, transference f', controlling rock-shaft d' turned in the direction of arrow 50 to effect filling-replenishment, the shuttle-

feeler Y mounted to rock on stud a and also to move laterally thereupon, the arm d¹² fast on the rock-shaft d' and bearing on the pin 30 on the shuttle-feeler, and the spring S', may be and are all substantially as in the 60 Roper patent and operate as therein set forth. The combined thread-parter and thread-clamp, indicated as a whole at C, Fig. 1, may also be substantially such as shown in said patent, and neither the parter and 65 clamp nor the other part of the mechanism described forms any novel part of my invention, and as all are well known no further description is necessary. Herein I have retained the upright, stationary arm E, Fig. 1, which 70 forms a part of the thread-catcher of the patent, dispensing with the other parts, the rearwardly extended head e' of the arm herein constituting a support for the severed 75 piece of thread and serving as the fixed member of the thread-remover. The co-operating member, in accordance with my invention, is shown as a brush comprising a hub 1 provided with bristles 2 and mounted to rotate on a horizontal stud 3 between ears 4 of a 80 stand 5 rigidly mounted on the breast-beam B of the loom and extended rearwardly above the support e', so that the bristles of the rotatable brush will sweep over the top 85 of said support. A circular ratchet 6 is secured to one end of the brush hub, to be acted upon by a pawl 7 formed on the rear end of a bent pawl-carrier 8 having a slot 9, Fig. 2, to receive the stud 3, a spring 10 between the 90 stud head 11 and pawl-carrier pressing the latter against a boss 12 on the outer side of the adjacent ear 4. The front end of the pawl-carrier is pivotally connected with one end of a lever 13 fulcrumed at 14 on the stand 5, the other end of said lever being 95 connected by a link 15 with the pin 30 on the shuttle-feeler Y, as shown in Fig. 1.

When filling replenishment is called for the rock-shaft d' is turned in the direction of arrow 50, Fig. 1, and the shuttle-feeler Y 100 is swung rearward on its fulcrum a to operatively position the thread parter and clamp C to act upon the old filling thread and part and clamp it near the shuttle. As the shuttle-feeler swings rearward the pin 30 105 rises and through link 15 the lever 13 is rocked to depress its rear end, thereby rocking the pawl-carrier 8 to elevate the pawl 7 and enable it to take hold of a new tooth of the ratchet 6, the slot 9 permitting a neces- 110

sliding motion of the pawl-carrier on the stud 3 at such time. The spring 10 yields as the pawl clicks over the ratchet teeth, and when the shuttle-feeler returns to normal position the lever 18 and pawl-carrier 8 are returned to the position shown, thereby effecting a partial rotation of the brush in the direction of arrow 60, Figs. 1 and 2. As the shuttle-feeler swings forward it causes the parted and clamped piece of thread to be drawn forward on the support ϵ' into position to be engaged by the brush and swept forward after the usual temple thread-cutter (not shown) has parted the piece of thread near the edge of the cloth. The intermittent rotative movement of the bristles 2 thus serves to push the severed pieces of thread forward along the support ϵ' , and they finally drop off at its front end, so that they cannot be caught by the fresh filling and woven into the cloth. To prevent undue freedom of movement of the brush a friction spring 16, Fig. 3, is provided, mounted on one of the ears 4 and bearing against the adjacent end of the brush hub 1.

The shuttle-feeler has a lateral as well as a rocking movement on the stud α and the pin 39 partakes of these movements, so that the link 15 is loosely connected with the pin, and by a guide 17 the link is held from improper sidewise movement, the guide being fixed on any part of the loom frame.

After the severed pieces of thread are swept forward by the brush to a position in front of it the shaking or jarring of the loom soon causes them to drop off the support ϵ' while they cannot move backward thereon on account of the brush.

The structure is simple and effective and the wear is comparatively slight, inasmuch as rotative movement of the brush is effected only when filling is replenished.

Having fully described my invention, what I claim as new and desire to secure by Letters Patent is:—

1. In an automatic filling-replenishing loom having a device to part and clamp the spent thread of filling upon filling replenishment, and means to actuate said device, in combination, a fixed support for the severed piece of thread, a rotatable member to sweep the severed piece of thread forward along the support, and means to effect intermittent rotation of said member.

2. In an automatic filling-replenishing loom having a thread-parting and clamping device bodily movable upon filling replen-

ishment into position to act upon the thread of filling to be abandoned, in combination, a thread-remover comprising a fixed supporting member for the severed piece of thread, a cooperating, intermittently rotatable member to sweep the piece of thread forward along the fixed member, and means to effect rotative movement of the rotatable member when filling is replenished.

3. In an automatic filling-replenishing loom having a thread parting and clamping device bodily movable upon filling replenishment into position to act upon the thread of filling to be abandoned, in combination, a thread-remover comprising a fixed support for the severed piece of thread, a rotatable brush mounted above and to sweep the upper face of the support, and means to effect rotative movement of the brush to thereby sweep forward pieces of thread sustained on the support.

4. In an automatic filling-replenishing loom having a thread parting and clamping device bodily movable upon filling replenishment into position to act upon the thread of filling to be abandoned, and operating means for said device, in combination, a fixed support for the piece of thread severed by the parting device, a rotatable brush to sweep the severed piece of thread forward along the support, actuating connections between the brush and said operating means, to effect intermittent rotation of the brush when replenishment of filling takes place.

5. In an automatic filling-replenishing loom having a shuttle-feeler, a thread parting and clamping device thereon bodily movable upon filling replenishment into position to part and clamp the filling thread to be abandoned, and means to govern movement of the shuttle-feeler, in combination, a thread-remover comprising a substantially horizontal, stationary thread support adjacent the shuttle-feeler path, a cooperating, rotatable brush having an attached ratchet, a pawl, a pivoted carrier on which it is mounted, and actuating means for said pawl-carrier, connected with and operated by movement of the shuttle-feeler into and out of operative position, to effect intermittent rotation of the brush.

In testimony whereof, I have signed my name to this specification in the presence of two subscribing witnesses.

JAMES MARCURE.
